UNITED STATES PATENT OFFICE.

LACY M. NORWOOD, OF SAVANNAH, GEORGIA.

COMBINED TRENCH-SHIELD AND HELMET FOR SOLDIERS.

1,177,888.

Specification of Letters Patent. Patented Apr. 4, 1916.

Application filed November 15, 1915. Serial No. 61,544.

To all whom it may concern:

Be it known that I, LACY M. Norwood, a citizen of the United States, residing at Savannah, in the county of Chatham and State of Georgia, have invented certain new and useful Improvements in Combined Trench-Shields and Helmets for Soldiers; and I do declare the following to be a full, clear, and exact description of the invention, 10 such as will enable others skilled in the art to which it appertains to make and use the same.

This invention relates to shields to be used as armor or protection for soldiers 15 while in battle.

One object of the invention is to provide a bullet deflecting shield which is particularly adapted for use in trench warfare.

Another object of the invention is to provide 20 a shield of this character which is equally adapted for use as a helmet while the soldiers are advancing or retreating in battle or are fighting in the open.

A further object of the invention is to provide 25 a combined trench shield and helmet which is foldable and light and which can be easily and conveniently transported when not being used.

A still further object is to provide a device 30 of this character which is simple, strong, durable and inexpensive to manufacture, efficient, reliable, and well adapted to the purpose for which it is designed.

With these and other objects in view the 35 invention consists of certain novel features of construction, and the combination and arrangement of parts which will be herein-after fully described and claimed.

In the accompanying drawings in which 40 similar reference characters designate like parts throughout the several views, Figure 1 is a side elevation of a device constructed in accordance with this invention showing the same set up for use at the top of a 45 trench; Fig. 2 is a bottom plan view of the device; Fig. 3 is a vertical longitudinal sectional view of the device showing it used as a helmet; Fig. 4 is a rear elevation of the device; and Fig. 5 is a sectional view taken 50 on the line 5—5 of Fig. 3.

The present invention comprises a pair of 55 bullet deflecting metal plates 1 and 2 which may be of any suitable configuration, but which are preferably, as here shown, of triangular shape. These plates 1 and 2 are hingedly or pivotally connected together

along one of their edges, and to this end, each of the former is provided with sockets 3, the latter being arranged in staggered relation and disposed in alinement to receive 60 pivot pins 4 and 5. The pivot pins may be permanently secured in position or they may be removable, in which event they are provided at their outer ends with eyes 6 which facilitate the removal of said pins. 65

The plates 1 and 2 are provided with laterally offset portions 7 along one of their edges, the portions of the former between their body portions and the offset portion 7 being provided with apertures 8 through 70 which are inserted pins 9, the intermediate portions of the latter being disposed adjacent said offset portion 7. This provides a simple and convenient manner in which to detachably secure the pins 9 to the shield 75 when the same is not being used.

The shield is provided with a port hole 10 at the apex of the angle formed between the plates 1 and 2. This porthole 10 may be of any desired shape and may be disposed 80 at any convenient place along said apex. Soldered, riveted or otherwise firmly secured to the inner side of the plates 1 and 2 are loops 11 through which are passed flexible straps 12, the latter being secured to 85 a flexible head band 13. Secured to the top of this head band 13 is a bullet proof metal plate 14, which is disposed directly beneath the porthole 10 for a purpose to be described, and the front of said head band is 90 provided with a similar plate 15. The back and sides of the head band may be provided with similar plates if desired. In addition to the apertures 8 in the plates 1 and 2, the latter are provided with apertures 16 95 and with notches 16' disposed between the former and in alinement therewith. Extending through the notches 16' are leather straps 17 having one of their ends secured to the sides of the head band 13 near the 100 lower edge thereof. The other end of one of the straps 17 is provided with a suitable buckle 18 which engages the other end of the other strap 17, and connects the same together. 105

When the device is to be used as a shield in trench fighting the head band 13 is unbuckled and moved aside so as to uncover the porthole 10. The device is then positioned at the top of the trench with the forward end pointing toward the enemy, the angle between the plates 1 and 2 being ad- 110

justed at the will of the operator, and the pins 9 being removed and inserted through the apertures 16 into the ground to peg the device thereto. The soldier in the trench 5 may thus observe the movement of the enemy through the porthole 10 or insert the muzzle of his rifle therethrough while firing without being in danger of being struck by one of the enemy's bullets, the angle of the 10 plates 1 and 2 being such as to deflect them into the air. If, however, the soldiers are advancing or retreating in battle, or are fighting in the open, the device may be worn as a helmet, the head band 13 fitting snugly 15 around the head and fastened on by the straps 17 which buckle under the chin. The metal plates 14 and 15 protect the top of the head and forehead of the wearer from bullets or fragments of shells which may 20 come through the porthole 10.

The device may be conveniently transported when it is not being used as it may be quickly and easily folded into a flat compact article, the head band collapsing between the inner sides of the plates 1 and 2.

From the foregoing, it may be seen that the objects of the invention have been effectively carried out, a light, simple, inexpensive and extremely useful combined trench 30 shield and helmet having been provided. However, it is to be understood that various minor changes in form and proportion may be resorted to without departing from the spirit of this invention, and hence I do not 35 wish to be limited to the construction herein shown and described other than that set forth in the appended claims.

I claim:—

1. The combination of a pair of pivotally 40 connected plates having a porthole therein at the apex of the angle formed between the former, and a head band detachably secured to the inner sides of said plates, substantially as and for the purpose set forth.

2. The combination of a pair of pivotally 45 connected plates having a porthole therein at the apex of the angle formed between the former, a head band detachably secured to the inner sides of said plates, and means for holding said head band on the head of a person, substantially as and for the purpose set forth.

3. The combination of a pair of pivotally 55 connected plates having a porthole therein at the apex of the angle formed between the former, a head band detachably secured to the inner side of said plates, and bullet proof metal plates secured to said head band to protect the head of the person wearing the latter, substantially as and for the purpose set forth.

4. The combination of a pair of pivotally 60 connected plates having a porthole therein at the apex of the angle formed between the former, a head band detachably secured to

the inner side of said plates, bullet proof metal plates secured to said head band, and means for holding the latter on the head of a person, substantially as and for the purpose set forth.

5. The combination with a pair of pivotally 70 connected triangular plates having a porthole therein at the apex of the angle formed between the former, a head band detachably secured to the inner side of said plates beneath the porthole therein, bullet proof plates secured to said head band, one of the former being disposed at the top of the latter directly beneath said porthole, and means for holding said head band on the 75 head of a person, substantially as and for the purpose set forth.

6. The combination with a pair of pivotally 80 connected triangular plates having a porthole therein at the apex of the angle formed between the former, the inner side of said plates being provided with loops, a head band having straps engaging said loops for detachably securing the former to said plates, bullet proof plates secured to said 85 head band, and means for holding the latter on the head of a person, substantially as and for the purpose set forth.

7. The combination with a pair of pivotally 90 connected triangular plates having a porthole therein at the apex of the angle formed between the former and slots near their outer edges, the inner sides of said plates being provided with loops, a head band having straps passed through said 95 loops for detachably securing the former to said plates, bullet proof plates secured to the top and sides of said head band, additional straps secured to the sides of the latter, said additional straps passing through said slots, and means for adjustably and detachably attaching the ends of said straps together substantially as and for the purpose set forth.

8. A folding portable shield of the class 100 described comprising a pair of pivotally connected triangular plates having a porthole therein at the apex of the angle formed between them, a head band detachably secured to the inner sides of said plates, pins for pegging said shield to the ground, and fastening elements securing said pins to said shield when the latter is not in use, substantially as and for the purpose set forth.

9. A folding portable shield of the class 110 described comprising a pair of bullet deflecting triangular plates pivotally connected together along one of their edges, said shield having a porthole therein at the apex of the angle formed between said plates, the latter being provided with a laterally offset portion 115 along another of their edges and provided with apertures at the portions connecting said offset portions with the body portions, a head band detachably secured to the inner sides of said plates, and pins for pegging 120

said shield in position to the ground, said pins being inserted through said apertures when said shield is not in use, the intermediate portions of the former being disposed adjacent the offset portions of said plates, substantially as and for the purpose set forth.

In testimony whereof I have hereunto set

my hand in presence of two subscribing witnesses.

LACY M. NORWOOD.
